UNITED STATES PATENT OFFICE.

GEORGE J. HELFRICH, OF CINCINNATI, OHIO.

HORSESHOE-CALK ATTACHMENT.

1,261,231.

Specification of Letters Patent.

Patented Apr. 2, 1918.

Application filed April 16, 1917. Serial No. 162,504.

To all whom it may concern:

Be it known that I, GEORGE J. HELFRICH, a citizen of the United States, residing at Cincinnati, in the county of Hamilton and 5 State of Ohio, have invented certain new and useful Improvements in Horseshoe-Calk Attachments; and I do declare the following to be a full, clear, and exact description of the invention, such as will enable others skilled 10 in the art to which it appertains to make and use the same.

This invention relates to certain new and useful improvements in calk attachments for horseshoes.

15 The primary object of the invention is to provide a calk attachment for horseshoes which can be easily and quickly applied to and removed from the horseshoes in connection with which it is to be used.

20 Another object of the invention is to provide a calk attachment which is adjustable to fit the various sizes and shapes of horse- shoes.

25 A further object of the invention is to provide an improved means for firmly clamping the attachment to the horseshoes.

30 A still further object of the invention is to provide a removable calk attachment which can be firmly attached to the bottom of the forward part of a horseshoe after the toe calk of the shoe has been entirely worn off, just as effectively as it may be attached when the toe calk is in good condition.

35 A further object of the invention is to generally improve upon devices of this character by the provision of a comparatively simple, strong, durable and inexpensive construction, one which will be efficient and reliable in operation, and well adapted to the 40 purpose for which it is designed.

45 With these and other objects in view, the invention consists of certain novel features of construction, and the combination and arrangement of parts which will be herein- after fully described and claimed.

50 In the accompanying drawings forming a part of the application and in which similar reference characters are used to designate like parts throughout the several views:—

Figure 1 is a bottom plan view of a horse- shoe, showing also in bottom plan view, a calk attachment constructed in accordance with this invention;

Fig. 2 is a sectional view taken on the line 55 2—2 of Fig. 1;

Fig. 3 is a sectional view taken on the line 3—3 of Fig. 1;

Fig. 4 is an elevation of the outer end of one of the calk-holding members; and,

Fig. 5 is a similar view of the inner side 60 of the hooked clamp plate.

Referring more particularly to the drawings, the letter A designates a horseshoe across the toe of which the attachment is shown mounted. This attachment comprises 65 a pair of calk-holding members 1 and 2, which are respectively provided with substantially countersunk openings 3 and 4, and removable in these openings 3 and 4 are calks 5 and 6 respectively. It is to be understood 70 that these calks may be of any desired form and the openings 3 and 4 may be changed in shape to accommodate any form, but for the purpose of illustration, the calks are provided with straight sharpened edges. 75

The member 1 as shown more clearly in Fig. 2 of the drawings is provided at its outer end with a hooked portion 7 which engages around the outer edge of the shoe, and at the upper extremity of this hooked 80 portion there are two points projecting inwardly and slightly upwardly, which points embed into the outer wall of the hoof near the top of the outer edge of the shoe. The inner end of the member 1 is provided with 85 an upwardly projecting boss 8 having a screw-threaded aperture 9 extending therethrough. Arranged in the body portion of the member 1 adjacent the inner end of the aperture 9 is a recess 10 which receives the 90 inner end of a screw 11 which projects from the inner end of the other calk-holding member 2. This screw 11 forms a shank-like connection or means for adjustably connecting the two calk-holding members together. 95

The calk-holding member 2 in addition to carrying the screw 11 at the inner end thereof, has a screw 12 extending from its outer end. This screw 12 extends through an enlarged opening 13 in a clamp member 14. As 100 shown, this clamp member 14 is provided with hook grips or points 15 at its upper extremity, projecting inwardly and slightly upwardly, which points embed into the wall of the hoof near the top of the outer edge 105 of the shoe, and the inner surface of this member engages against the top of the outer edge of the shoe. A suitable nut 16 forms the tightening means for holding the member 14 in clamped position, and if desired, a 110

lock washer 17 may be employed to prevent loosening of the nut after it has been tightened.

As clearly shown by Fig. 4 of the drawings, the outer end of the member 2 is provided with downwardly inclined ribs 18, these ribs 18 fitting into inclined recesses 20 arranged in the inner face or side of the clamp member 14, whereby when said clamp member is moved into tight frictional engagement with the member 2, the ribs and recesses coöperate and cause the clamp member 14 to be moved downwardly and inwardly, causing the hooks at the upper extremity of this member to embed firmly into the outer wall of the hoof, and the inner surface of the upper extremity of this member, just below the hooks or points, to engage against and over the top of the outer edge of the shoe and which obviously will cause the upper side of the member 2 to be tightly engaged with the lower side of the horseshoe, and to hold the calk 6 in place, this construction forming the subject-matter 25 of U. S. Patent No. 1,038,883, granted to me on September 17, 1912.

As shown in Fig. 2 of the drawings, the claws of the hooked portion 7 of the member 1 are arranged at upward incline, and 30 this is sufficient to similarly cause the upper face of the member 1 to be fitted snugly against the lower side of the horseshoe and to maintain the calk 5 in place.

The reference numeral 21 designates a substantially J-shaped spacing member, the shank portion of which is provided with an opening 22 into which the aforesaid screw 11 extends. The foot or base of this spacing member 21 is provided in its inner side with 40 a recess 23 which receives the adjacent edge of the member 1, said recess being shaped to conform to the shape of this edge of the member 1. The outer face or side of the foot or base of the spacing member 21 is provided with a recess 24 which receives the inner edge of the toe of the horseshoe.

By reason of the screw 11 connecting the two calk-holding members 1 and 2, these members are adjustably connected with each other so that the attachment may be adjusted to fit horseshoes of various widths. The adjusting is to be done before the device is applied to the shoe, as obviously the member 2 could not be turned so as to operate the 55 screw 11 when it is applied.

If the device is to be attached to a shoe with a comparatively good toe calk, it will not slip forward any appreciable amount, as the two calk-holding members would be brought to bear with their forward sides 60 against the toe-calk of the shoe, and it would be held stationary there. Owing to the peculiar shape of this device, the center being the back of a line with its extremities at the 65 points of their contact with the outer edges

of the shoe, and the further fact that the outer edges of the shoe at these points of contact curve inwardly toward the front, without some brace this device would work forward and become loose. To overcome 70 this and also to cause the device to pivot more freely so that in tightening it will not bind, but will take up all slack or loose motion, the spacing member 21 is provided. This member 21 engages the inner edge of 75 the toe of the horseshoe and prevents any forward movement of the entire attachment. By reason of the fact that the member 21 has a threaded connection with the screw 11, the former may be adjusted upon the latter 80 to move it toward or away from the central longitudinal axis of the shoe or to a place where it may engage any desired point on the inner edge of the shoe. Thus, the spacing member 21 is adjustable so that it may 85 be effectively used with horseshoes of various shapes as well as sizes. It will be noted that in order to adjust this member, it is necessary to remove the device from the horseshoe and to unscrew the member 2, in 90 view of the fact that one edge of the member 1 fits into a recess 23 in the inner side of the foot or base of the member 21 and prevents the latter from turning when the member 1 is in place.

From the foregoing, taken in connection with the accompanying drawings, it will be seen that the construction and use of the invention will be readily understood.

As various changes in form, proportion, and in the minor details of construction may be resorted to without departing from the spirit of this invention, I do not wish to be limited to the precise construction herein shown and described.

I claim:—

1. An attachment for horseshoes adapted to be mounted transversely across the fore part of the shoe, including two calk-holding members adapted to hook around the outer edge of the shoe and being connected together, and a spacing member in conjunction with said calk-holding members and adapted to engage the inner edge of the toe of the shoe, said spacing member being adjustably movable between said calk-holding members toward and away from the same.

2. An attachment for horseshoes adapted to be mounted transversely across the fore part of the shoe, comprising two calk-holding members adapted to hook around the outer edge of the shoe, a shank-like connection connecting said members together, and a spacing member movable longitudinally upon said connection and adapted to engage the inner edge of the toe of the shoe, said spacing member being disposed between said calk-holding members and adjustable toward and away from the same.

3. An attachment for horseshoes adapted

to be mounted transversely across the fore part of the shoe, comprising two calk-holding members adapted to hook around the outer edge of the shoe, a screw adjustably connecting said members together, and a spacing member adapted to engage the inner edge of the toe of the shoe and having a threaded connection with said screw, whereby it is adjustably movable with respect to 10 the latter.

4. An attachment for horseshoes adapted to be mounted transversely across the fore part of the shoe, comprising two calk-holding members adapted to hook around the outer edge of the shoe, a screw adjustably connecting the inner ends of said members together, and a J-shaped spacing member having its shank portion in threaded engagement with the portion of said screw disposed between the inner ends of said members and its base portion concaved to receive the inner edge of the toe of the shoe.

5. An attachment for horseshoes adapted to be mounted transversely across the fore part of the shoe, comprising two calk-holding members having upwardly extending hooked portions on their outer ends adapted to hook around the outer edge of the shoe, the inner end of one of said members being provided with an upwardly extending boss and a recess in its upper side adjacent said boss, a screw formed integral with and projecting from the inner end of the other member, said screw having threaded engagement with said boss and having its free end received in said recess, and a spacing member adapted to engage the inner edge of the toe of the shoe and having a threaded engagement with said screw, whereby it is adjustably movable with respect to the latter.

6. An attachment for horseshoes adapted to be mounted transversely across the fore part of the shoe, comprising two calk-holding members adapted to hook around the outer edge of the shoe, a screw adjustably and detachably connecting the inner ends of said members together, and a J-shaped spacing member having its shank portion in threaded engagement with the portion of said screw disposed between the inner ends of said calk-holding members, the inner edge of the base portion of said spacing member being shaped to conform to the shape of the adjacent edge of one of said calk-holding

members and engaging the same to prevent 55 said spacing member from turning with respect to the latter, the outer edge of the base portion of said spacing member being concaved to receive the inner edge of the toe of the shoe.

7. An attachment for horseshoes adapted to be mounted transversely across the fore part of the shoe, comprising two calk-holding members adapted to hook around the outer edge of the shoe, a screw adjustably 65 connecting the inner ends of said members together, and a J-shaped spacing member having its shank portion in threaded engagement with the portion of said screw disposed between the inner ends of said members and 70 its base portion concaved to receive the inner edge of the toe of the shoe.

8. An attachment for horseshoes adapted to be mounted transversely across the fore part of the shoe, comprising two calk-holding 75 members coupled together and one of them being adapted to hook around the outer edge of the shoe, a spacing member connected to said calk-holding members and adapted to engage the inner edge of the toe of the shoe, 80 and a clamp member adapted to be disposed and to hook around the outer edge of the shoe and detachably and adjustably connected to the other calk-holding member to hold said calk-holding members to the shoe.

9. An attachment for horseshoes adapted to be mounted transversely across the fore part of the shoe, comprising two calk-holding members coupled together and one of them being adapted to hook around the outer 90 edge of the shoe, a spacing member connected to said calk-holding members and adapted to engage the inner edge of the toe of the shoe, a screw extending longitudinally from the outer end of the other calk-holding member, 95 a clamp member carried upon said screw and adapted to be disposed and to hook around the outer edge of the shoe, and a nut threaded upon said screw and engaging said clamp member to hold the same in clamping 100 engagement with the shoe.

In testimony whereof I have hereunto set my hand in the presence of two subscribing witnesses.

GEORGE J. HELFRICH.
